UNITED STATES PATENT OFFICE.

GEORGE E. MITTINGER, OF YOUNGSTOWN, OHIO, ASSIGNOR OF FIFTEEN-SIXTEENTHS
TO PRESSED STEEL PRODUCTS COMPANY, OF SHARON, PENNSYLVANIA.

DESIGN FOR A FAUCET-CASING.

52,919.

Specification for Design.

Patented Jan. 28, 1919.

Application filed May 4, 1916. Serial No. 95,506. Term of patent 14 years.

To all whom it may concern:

Be it known that I, GEORGE E. MITTINGER, a citizen of the United States, residing at Youngstown, in the county of Mahoning and State of Ohio, have invented a new, original and ornamental Design for Faucet-Casings, of which the following is a specification, reference being had therein to the accompanying drawing.

Figure 1 is a perspective view.

Fig. 2 is a side elevation.

I claim:

The ornamental design for a faucet casing substantially as shown.

In testimony whereof I hereunto affix my signature in the presence of two witnesses.

GEORGE E. MITTINGER.

Witnesses:

MARY R. RYSER,
GEO. J. CAREW.
